DESIGN FOR A DISPLAY FIGURE

Dikran Dingilian, New York, N. Y., assignor to James Lees and Sons Company, Bridgeport, Pa.,
 a corporation of Pennsylvania

Application May 25, 1948, Serial No. 146,567

Term of patent 7 years

(Cl. D1—2)

To all whom it may concern:

Be it known that I, Dikran Dingilian, a citizen of the United States, residing in New York city, State of New York, have invented a new, original, and ornamental Design for a Display Figure, of which the following is a specification, reference being had to the accompanying drawing, forming part thereof, in which

Figure 1 is a front elevation of a display figure, showing my new design;

Fig. 2 is a rear elevation; and

Fig. 3 is a side view on a reduced scale.

I claim:

The ornamental design for a display figure, as shown.

DIKRAM DINGILIAN.
